UNITED STATES PATENT OFFICE.

JAMES H. HURTT, JR., OF PHILADELPHIA, PENNSYLVANIA, ASSIGNOR TO THE DENTAL
MANUFACTURERS SUPPLY CO., A CORPORATION OF PENNSYLVANIA.

DESIGN FOR A CHEMIST'S MORTAR.

52,957.

Specification for Design.

Patented Feb. 4, 1919.

Application filed October 4, 1918. Serial No. 256,911. Term of patent 7 years.

To all whom it may concern:

Be it known that I, JAMES H. HURTT, Jr., a citizen of the United States, residing in Philadelphia, in the county of Philadelphia and State of Pennsylvania, have invented a new, original, and ornamental Design for a Chemist's Mortar, of which the following is a specification, reference being had to the

accompanying drawing, forming a part thereof.

Figure 1 is a perspective view and Fig. 2 an elevation showing my improved design.

I claim:

The ornamental design for a chemist's mortar as shown.

JAMES H. HURTT, JR.
